UNITED STATES PATENT OFFICE

ALMA E. BRANDHORST, OF CINCINNATI, OHIO

DESIGN FOR A PARKING LIGHT

Application filed March 28, 1932. Serial No. 43,314. Term of patent 7 years.

To all whom it may concern:

Be it known that I, ALMA E. BRANDHORST, a citizen of the United States, residing at Cincinnati, in the county of Hamilton and State of Ohio, have invented a new, original, and ornamental Design for Parking Lights, of which the following is a specification, reference being had to the accompanying drawing, forming a part thereof.

Fig. 1 is a front elevation of a parking light, showing my new design.

Fig. 2 is a perspective view of the same.

I claim:

The ornamental design for a parking light, as shown.

ALMA E. BRANDHORST.
